No. 652,930.

Patented July 3, 1900.

J. J. SOUDER.
DUMPING CAR.

(Application filed Apr. 28, 1899. Renewed Dec. 6, 1899.)

(No Model.)

UNITED STATES PATENT OFFICE.

JACOB J. SOUDER, OF WASHINGTON, DISTRICT OF COLUMBIA.

DUMPING-CAR.

SPECIFICATION forming part of Letters Patent No. 652,930, dated July 3, 1900.

Application filed April 28, 1899. Renewed December 6, 1899. Serial No. 739,439. (No model.)

To all whom it may concern:

Be it known that I, JACOB J. SOUDER, a citizen of the United States, and a resident of the city of Washington, in the District of Columbia, have invented new and useful Improvements in Dumping-Cars, of which the following is a full and correct description.

The invention has relation generally to dumping-cars and particularly to cars of this class which are designed for the transportation in bulk of coarse and heavy materials—such as coals, ores, and the like, as distinguished from the cereals and other fine granular matter. A type of cars of this class is found in United States Patent No. 464,086, which was issued to me on the 1st day of December, 1891. That car has been found in its essential functions to operate satisfactorily; but in some instances objection has been made to the location of the door-closing mechanism within the interior space of the hopper and also to the occupation of an important portion of the central space of the car by the longitudinal central sill. Accordingly the construction of the hopper has been modified by the substitution for the transversely-rectangular sill of a transversely Δ -shaped or inverted-V-shaped centrally-located metallic support which divides the lower portion of the chamber of the car into two parts and which extends from end to end of the hoppers proper in their discharging portion, while the winding-shaft and its lifting-chains have by the adoption of this construction been transferred from the interior to the exterior of the car.

The invention relates also to various novel parts or combinations of parts embraced in the details of construction of the car, as will appear from the following description and from the several paragraphs which succeed the same.

In the accompanying drawings, which constitute a part of this specification, Figure 1 represents a car of the "gondola" or "elevated-end" pattern, to which my newly-invented improvements have been applied, the view being in part in side elevation and in part in vertical longitudinal central section. Fig. 2 is a transverse section through the hopper-discharging portion of the car and looking toward the inclined face of the interior of

the same. Fig. 3 is a detail of one end of the hopper as seen before the central Δ -shaped supporting rib or girder has been attached thereto. Fig. 4 is a view of the lower or primary member of the compound Δ -shaped supporting rib or girder detached. Fig. 5 is a perspective view of the auxiliary surmounting-rib or crown-piece detached. Fig. 5^a is an edge view of one of the transversely-extending binding and supporting bars or "chute-irons," which by their hooked extremities engage and rest upon the outer sills of the car. Fig. 6 is a perspective view of a bearing-frame or reinforce which is applied within the open Δ -shaped portion of the transverse supporting-bars or chute-irons. Fig. 7 is a view of the door-closing shaft and of the actuating-shaft to which it is geared detached.

As best seen in Figs. 1 and 2, the side walls *sw* of the car *a* are in this instance placed vertically along the sides or outer boundaries of the hopper, while each opposite one-half of the hopper *h* is downwardly inclined from a point near the upper extremity of the car-frame and to a point within the inner vertical plane of the track-wheels, whence it is extended vertically downward to a point substantially in horizontal plane with the axles of such wheels. At each extremity of the discharging-opening of the hoppers *hh* a chute-iron or bearing-bar *chi*, having angular terminal hooks *ho* and being immediately of the depressed or flattened **W** shape represented in Fig. 5^a, extends across the bed-frame space and has perforations to permit it to receive and to be securely riveted to the flanges *hf* upon the corresponding vertical portion *hv* of the hopper. Extending from end to end of the discharging portion of the hopper is the primary Δ -shaped metallic girder *cs*, which bestrides the upwardly-extending Δ -shaped central portion *as* of the chute-iron or bearing-bar *chi*, each of these parts being provided with suitable perforations to permit them to be firmly riveted together. To still further strengthen this central rib-like or fin-like girder, the auxiliary Δ -shaped reinforce or crown-piece *cp* is mounted astride the primary member or girder *cs*, and this secondary member or crown-piece is riveted to both the chute-iron *chi* and the primary girder *cs*.

The hopper-doors *hd* are at their upper extremity made fast to hinge-plates *hp*, which are secured to outer sills *os* *os*, and at their inner extremity are provided with lifting-chains *lc*, which are connected to an elevating-shaft *es*, which is supported in suitable hangers *ha* of the center sill *ces* and which is operated by a winding-shaft *ws*, to which it is suitably geared, as seen in Fig. 1 and 7.

10 In Figs. 2 and 6 is seen a triangular brace-frame *tf*, which is adapted to the A-shaped space within the A-shaped portion of the chute-iron and is auxiliary to the outwardly-resisting strength of the chute-iron and to the chain mechanism shown and already described. This brace-frame *tf* is in practice provided with a narrow base, as is best seen in Fig. 2, to adapt it to the corresponding narrow space in the chute-iron. In its base 15 it has a swivel-pin *sp*, a swivel-arm *sa*, oppositely-projecting supporting-lugs *ol ol*, and an operating-rod *or*. This swivel-arm, together with its related mechanism, is similar to that shown and described by me in an 20 application for patent, serially numbered 714,072, filed by me in the United States Patent Office on the 22d day of April, 1899, and it is adapted to be employed in connection 25 with the closing-doors in the same manner; but it is not herein claimed as novel.

Except as hereinbefore provided the bed-frame *bf*, including the longitudinal center sills or half-sills *lcs*, the outer sills *os*, and the transverse sills *ts* may be of the ordinary 30 construction of this class of cars.

In the operation of the parts when the swivel-bar is moved from its engagement with the supporting-lugs *ol ol* the hopper-doors *hd* will be released from their position, as seen 35 in Figs. 1 and 2, and the chains being also released the doors will fall and the contents of the hopper will be discharged. The chains being then again wound upon the shaft, the doors will thereby be closed, when the swivel-bar may be moved to its engaging position, 40 its ends resting upon the lugs *ol ol*, as before.

The invention having been thus particularly described, what is claimed is—

1. In a dumping-car, the combination with 45 the bed-frame of the car, of the oppositely-

placed metallic end sections, having inclined and vertical portions as described; the chute-irons, resting upon opposite parts of the bed-frame, and placed in coincidence with the vertical ends, to support the same, and the compound girder, flanged as specified, engaged with the flanges upon the end sections, and extending from end to end of the discharge-opening of the hopper; substantially 55 as set forth.

2. In a dumping-car, the combination with the bed-frame, and with the vertical frame of the car; of the hopper, embracing oppositely-placed end sections, each comprising an inclined and a vertical portion, facing the center of the car, the vertical portion having outstanding flanges as described; a transversely-extending supporting-bar or chute-iron, adapted to be united to the flanges of the end section, and the described girder, A-shaped 65 in transverse section, having end flanges as shown, extending from end to end of the vertical portion of the hopper, striding the central portion of the chute-iron, and the superposed outstanding flange, and united to 70 the flange, and to the vertical portion of the end section; substantially as shown.

3. In a dumping-car, a hopper which in its discharging portion is provided with a central support or girder which is composed of 80 metallic plates, and is of A shape in transverse section, and is rigidly attached to the end walls of such discharging portion.

4. In a dumping-car, a hopper which in its discharging-opening has a metallic transversely-A-shaped girder, which is in plane with the center sill of the car, and which is composed of two sections, one of which is received within the other, and each of which is secured to the vertical end portion of the discharging-opening of the hopper.

In testimony whereof I have hereto, at Washington, District of Columbia, on this 26th day of April, 1899, in the presence of two 85 subscribing witnesses, affixed my signature. 95

JACOB J. SOUDER.
